THE S. H. THOMSON MANUFACTURING COMPANY, OF DAYTON, OHIO, A CORPORATION
OF OHIO

SPRING CATCH FOR METAL SASH HARDWARE

Application filed December 16, 1930. Serial No. 502,744.

This invention relates to new and useful improvements in spring catches for metal sash.

It is one of the principal objects of our invention to provide for metal sash a compact and attractive spring catch structure including a bolt or plunger, preferably square in cross section, that is held within a broached hole in a rectangular case or barrel for entrance at its front end into a keeper but which does not protrude from the barrel at its rear end.

It is another object of our invention to provide a plunger-engagement finger that is integral with the handle, thereby making the device very simple and durable.

Other important and incidental objects will be brought out in the following specification and particularly set forth in the subjoined claims.

In the accompanying drawing illustrating our invention Figure 1 is a perspective view of our latch structure, showing the plunger in engagement with the keeper. Figure 2 is a longitudinal sectional view taken through the plunger barrel, showing how the plunger is engaged by the finger which is integral with the handle. Figure 3 is a cross sectional view taken on the line 3-3 of Figure 2, showing how the forked end of the handle finger straddles the plunger spring. And Figure 4 is a top plan view of the handle and plunger unit.

Referring to the accompanying drawing for a detailed description of our invention, the numeral 1 designates a barrel that is preferably rectangular in section and formed with two apertured side ears 2, 2 for attachment to a metal sash 3 by means of screws 4.

Integrally formed with the front portion of the barrel 1 are two parallel outwardly projecting lugs 5, 5. These lugs are formed with oppositely disposed holes to receive a transverse fulcrum pin 6 for an enlarged portion of a curved handle 7. Integral with the latter below the pin 6 is a radial finger 8 terminating in a forked portion 9 which fits in a tapered or V slot 10 in a plunger or bolt

11 that is preferably square in cross section.

This plunger is free to move longitudinally within a broached hole in the barrel 1 which is closed at its rear end to prevent a protrusion of the plunger from that end. The plunger, however, does protrude from the front end of the barrel to engage its beveled end 12 in a hole in a strike plate 13 of a keeper 14 secured to a frame 15 by screws 16.

Axially mounted within the barrel 1, and engaging its rear wall, is a helical spring 17 which fits in an axial bore 18 in the plunger. This bore terminates at its front end in a conical recessed part 19 of the front wall of the plunger. The front end of the spring engages this recessed front part of the plunger to force the front end 12 of the latter into the hole in the strike plate of the keeper 14.

The forked portion 9 of the finger 8 on the handle 7 straddles the spring 17 within the V slot 10 in the plunger so that when the handle is raised, the finger will engage the rear wall of the V slot to force the plunger rearwardly against the compressed spring, to withdraw the plunger from engagement with the keeper. The finger 8 being in one piece with the handle 7, conduces to a simple and durable construction that is made more compact by closing the rear end of the barrel against the protrusion of the rear end of the plunger.

Having described our invention, we claim:

1. A device of the type described, comprising a barrel closed at its rear end, a plunger square in cross section in said barrel and free to move out of its front end, said plunger formed with an axial hole extending inwardly from its rear end to a point well near its front end, a V slot in the upper portion of said plunger opening into said axial hole, a helical spring projecting from the rear wall of said barrel into the axial hole in the plunger, ears projecting outwardly from said barrel over the V slot, a handle pivotally secured between said ears, and a finger integral with the inner end of said handle and having a forked portion for entrance into said V slot to straddle the spring for the purpose specified.

2. A device of the type described, comprising

ing a barrel closed at its rear end, a plunger in said barrel and free to move out of its front end, said plunger formed with an axial hole extending inwardly from its rear end to a point well near its front end, said plunger also formed with a slot opening into the axial hole, a helical spring projecting from the rear wall of said barrel into the axial hole in the plunger for contact with the front wall of the latter, a handle pivotally secured to said barrel, and a forked portion on the inner end of said handle for entrance into said slot to straddle the spring, which projects beyond the forked end of the barrel in both directions.

In testimony whereof we have hereunto set our hands this 15th day of December, 1930.

ROBERT H. HUMMERT.
GEORGE E. GRAVENSTINE.
